(57) **CLAIM**

The ornamental design for a drawing board with clips as shown and described.

DESCRIPTION

FIG. 1 is a front perspective view of a drawing board with clips;

FIG. 2 is a back perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof;

FIG. 8 is a right side view thereof;

FIG. 9 is a front perspective view of an alternate configuration thereof;

FIG. 10 is a back perspective view of an alternate configuration thereof;

FIG. 11 is a front view of an alternate configuration thereof;

FIG. 12 is a back view of an alternate configuration thereof;

FIG. 13 is a perspective view in a folded state with clips removed; and,

FIG. 14 is a perspective view in a folded state with clips removed.

The broken lines in the drawings depict portions of the drawing board with clips that form no part of the claimed design.

The drawing board with clips is shown with a break in the length. The appearance of any portion of the article between the dot-dashed lines forms no part of the claimed design.

1 Claim, 14 Drawing Sheets
